UNITED STATES PATENT OFFICE.

HAROLD J. LE VESCONTE, OF CHARLESTON, WEST VIRGINIA, ASSIGNOR, BY MESNE ASSIGNMENTS, TO TIREGAGE VALVE CORPORATION, OF CHARLESTON, WEST VIRGINIA, A CORPORATION OF WEST VIRGINIA.

PNEUMATIC-TIRE PRESSURE GAUGE.

Application filed October 30, 1922. Serial No. 597,745.

To all whom it may concern:

Be it known that I, HAROLD J. LE VESCONTE, a citizen of the United States, residing at Charleston, in the county of Kanawha and State of West Virginia, have invented new and useful Improvements in Pneumatic-Tire Pressure Gauges, of which the following is a specification.

This invention is designed to improve the construction of pneumatic tire stem pressure gauges, particularly the type of pressure gauges having a movable plunger indicating the pressure and an expansible tube continuing the conduit through the plunger to the stem. With such constructions it is common to resist the movement of the plunger by means of a spring. These gauges being mounted in pneumatic tire stems necessarily have very limited space. The present invention is directed to a means of connecting the spring to the plunger which simplifies this attachment.

The invention is illustrated in the accompanying drawings as follows:—

Fig. 1 shows a vertical section through the pressure gauge.

Fig. 2 an enlarged view of the end of the plunger.

1 marks the stem. This is screwed into a screw-threaded socket in the head 2. A clamping plate 3 opposes the head in the usual manner. A spreader plate 4 is arranged over the clamping plate and a clamping nut 5 exerts clamping action on the clamping plate. The plunger 6 has a conduit 7 extending through it in which is arranged the usual inflation valve 8. The end of the plunger is screw-threaded making it suitable for receiving the pump and the usual cap 9 is screwed on to the end of the plunger when in normal use. The plunger is provided with a key-way 10 which engages a depression 11 in the stem to prevent it from turning so as to receive the pump as it is screwed into place. These features have heretofore been used in pressure gauges of this type.

The plunger has a reduced extension 12 on its lower end over which a tube 13 is placed, the tube being secured in place on the extension by a wrapping 14 which binds the tube to the extension, the extension having preferably a shoulder at its end to facilitate the securing of the tube. The

lower end of the tube is arranged over a reduced extension 15 on an anchor piece 16 by a wrapping 17, the anchor piece extending into a tapered opening 18 in the head 2 so as to make a closure at this point. The anchor piece has an opening 19 through it communicating with the tube 13.

A spring 20 is screwed on to a screw-threaded shoulder 21 on the anchor piece and the upper end of the spring is contracted at 22 so as to engage the upper end of the tube 13 so that the securing of the tube to the extension also secures the spring on the extension. The wrapping of the tube in binding it to the reduced extension forms a shoulder 23 at its end which is engaged by the contracted coils of the spring. The contraction of the coils may be accomplished prior to the placing of the spring over the tube, the coils being expanded for this purpose or the coils may be contracted into place after the spring is in place on the plunger. This method of attachment not only makes one of simplicity and convenience, the plunger being provided with no securing feature for the spring itself but at the same time permits of a close relation between the expansible tube and the spring.

It will be noted that the bottom of the key-way 10 is above the edge of the threads on the end of the plunger. This facilitates the forming of the key-way.

What I claim as new is:—

1. In a pneumatic tire pressure gauge, the combination of a hollow stem; a plunger slidingly mounted in the stem and indicating by its movement the gauge pressure, said plunger having a conduit therethrough; an expansible tube secured to the plunger; and a spring secured to the plunger through engagement with the tube and resisting the movement of the plunger.

2. In a pneumatic tire pressure gauge, the combination of a hollow stem; a plunger slidingly mounted in the stem and indicating by its movement the gauge pressure, said plunger having a conduit therethrough; an expansible tube having its end secured to the plunger; and a spring resisting the movement of the plunger secured to the plunger through engagement with the end of the tube that is secured to the plunger.

3. In a pneumatic tire pressure gauge, the combination of a hollow stem; a plunger slidingly mounted in the stem and indicating by its movement the gauge pressure, 5 said plunger having a conduit therethrough; an expandible tube having its end secured to the plunger; and a coil spring secured to the plunger through engagement with the tube by having coils contracted to engage 10 the end of the tube.

4. In a pneumatic tire pressure gauge, the combination of a hollow stem; a plunger slidingly mounted in the stem; an expandible tube having its end secured to the 15 plunger, the end of the tube being provided with a shoulder; and a coil spring arranged over the tube and secured to the plunger through engagement with the tube by having a coil contracted to engage the end of the tube.

ing coils contracted to engage the shoulder on the tube.

5. In a pneumatic tire pressure gauge, the combination of a hollow stem; a plunger slidingly mounted in the stem and indicating by its movement the gauge pressure, 25 said plunger having a conduit therethrough and a reduced extension on its lower end; a rubber tube arranged over the extension and secured thereon; and a coil spring resisting the movement of the plunger and arranged over the tube and secured to the 30 plunger through engagement with the tube by having a coil contracted to engage the end of the tube.

In testimony whereof I have hereunto set my hand.

HAROLD J. LE VESCONTE.
